TOY SAW MILL

Raymond E. Milligan, Houston, Tex., assignor to Lionel Corporation, New York, N.Y., a corporation of New York

Application October 30, 1957; Serial No. 693,425

9 Claims. (Cl. 46—39)

The present invention relates to a toy accessory and is more particularly related to a device for simulating the appearance and audible sound of the cutting of rough timber or logs in a lumber mill into smooth or finished planks or boards.

In carrying out such an operation, the rough timber or lumber is shifted from its feeding station, where it is visible, to a lumber cutting mill from which it is conveyed to a discharge station where it is obscured from view. Finished lumber planks, or similar dimensions to the rough timber are initially held at the feeding station obscured from view, and are, by the same means which convey the rough lumber planks simultaneously transported through the same mill to the discharge station where they are visible.

When the finished planks or boards are in a position where they are visible, additional means are provided to stack the lumber in such a manner as to prepare it for pick-up and loading into transportation means.

The accompanying drawings show, for purposes of illustrating the present invention, one embodiment in which the invention may take form, it being understood that the drawings are illustrative of the invention rather than limiting the same.

In the accompanying drawings:

Fig. 1 is a perspective view of the lumber mill; Fig. 2 is a front view of the invention as shown in Fig. 1 with parts broken away;

Fig. 3 is a top plan view of the invention as shown in Fig. 1 with parts broken away;

Fig. 4 is a sectional view taken along the line 4—4 of Fig. 3;

Fig. 5 is a top plan sectional view of a portion of the invention as shown in Fig. 1 with parts broken away;

Fig. 6 is an enlarged sectional view taken along the line 6—6 of Fig. 2;

Fig. 7 is an enlarged sectional view taken along the line 7—7 of Fig. 6;

Fig. 8 is an enlarged sectional view taken along the line 7—7 of Fig. 6 after the operation of certain of the parts; and

Fig. 9 is an enlarged sectional view taken along the line 9—9 of Fig. 2.

In Fig. 1 is shown a toy lumber mill device, indicated generally at 10, having a simulated cutting mill 12 at a point substantially intermediate its length. The device can be made of metal, fibre plastic or other suitable material which can have its exterior surface painted or otherwise decorated in any desired manner. As the specification proceeds, it will be noted that I have described my lumber mill device as constructed from metallic materials. However, it is understood that this has been done for simplicity of expression and that manufacture of the mill from other materials as hereinabove set forth is fully within the spirit of my invention.

The mill 12 forms the housing for electrical motor 14 and reduction gearing 16 (Fig. 2) which causes the automatic operation of the device to be hereinafter described.

2

The mill 12 is mounted on base portion 17 which extends the full length of the device. As seen in Figs. 1 and 9, this base portion has a bottom wall 18, a front wall 19 and a downwardly and rearwardly sloping top wall 20 forming the hollow interior 22. The mill 12 is welded or by other suitable means affixed at 25 to the upper surface of wall 20 so that front wall 26 of the mill is substantially parallel to and integrally connected with wall 19.

Extending laterally to one side of the mill 12, and by welding, soldering or other suitable means affixed thereto, is the lumber feeding or storage station 28 wherein is held the rough lumber open to view and also the finished planks hidden from view.

The rear section 29 of the lumber storage station 28 is similar to the base portion 17 in that it has a hollow interior 30 (Figs. 2 and 9) bounded by a front wall 32, a top wall 34 and a rear wall 36. This rear wall 36 is parallel to the rear wall 38 of base portion 17.

An end section 39, likewise having a hollow interior 40, includes an inner wall 41, an outer wall 42, a top wall 46 and a downward sloping forward wall 48. Top wall 46 of end section 39 integrally joins the top wall 34 of rear section 29 to form a continuous surface. The rear section 29 and end section 39 can be made as a molded piece or can be made of individual members to be soldered, welded or by other suitable means integral joined.

An L-shaped partition wall 50 (Figs. 1, 2, 9) extends between the side wall 27 of mill 12 and the inner wall 41 of end section 39, substantially parallel to front wall 32 of the rear section 29. This L-shaped wall 50 may be joined to walls 27 and 41 by welding or other suitable means.

This L-shaped wall 50 or bracket forms a pocket 54 (Fig. 9) wherein is retained, obscured from view, the finished lumber planks 60. These finished planks 60 rest on the lower substantially horizontally extending portion 51 of the bracket 50 and are freely slideable

under action of a mechanism to be later described. The rough lumber 62 (Fig. 1) rests in open view on the downwardly sloping surface of wall 20 of station 28. The rear edge wall 20 is flanged upwardly at 63 to form a pick-up recess 21 for the rough lumber 62. These rough logs, representing tree trunks, roll down surface 20 to rest in recess 21 substantially under the planks 60 resting in pocket 54.

Wall 27 terminates at 66 to provide opening 67 to allow the logs 62 and lumber 60 to pass through into the mill 50. 12 and a similar cooperating opening (not shown) is provided in wall 68 of mill 12 so that the station 28 and lumber discharge station 70 to be hereinafter described, are in free and open communication.

A mechanism, to be later described, grasps one log 55, 62 and one plank 60 and moves them in the direction of arrow 64 (Fig. 1). The visible rough log 62 then appears to enter the saw mill 12 through opening 67 while the smooth plank 60 moving simultaneously, is hidden from view behind partition wall 50.

Extending laterally from side wall 68 of mill 12 and by welding, soldering or other suitable means affixed thereto is a finished lumber discharge station 70 (Figs. 1, 2, 7 and 8). The top wall 20 of base section 17 of station 70 slopes downwardly and is turned upwardly at 71 (Fig. 7) only slightly as compared with the flange 63 of the wall 20 of station 28. At a point intermediate of wall 20 of station 28 is an upwardly projecting sloped wall 72.

The rear section 73 of station 70 has a rear wall 76 (Fig. 7) and top wall 78. Top wall 78 has a downwardly projecting flange 80.

Connected to the walls 76, 78, 80 of rear section 73

and walls 18, 19 and 20 of base section 17 of station 70 is a flat end wall 82.

A pivotable member 84 (Figs. 2, 5, 7) is mounted by pins 86 to the mill wall 68 opposite to wall 26 and end wall 82. This pivotable member has a flat portion 90, in substantially the same plane as the lower end 51 of bracket 50 hereinbefore described, an upwardly flanged portion 92 and a downwardly sloping forward extension 94.

In operation, when a lumber plank 60 has been transferred from hidden pocket 54 through mill 12 through openings in walls 26 and 68, it will come into view as it slides onto flat portion 90 of member 84. By means to be later described, member 84 is pivoted about the pin 86 (Fig. 8) so that plank 60 will slide off member 84 down the sloping wall 72 and come to rest in wall 20 in a position indicated at 60' (Figs. 1 and 3).

At the same time the rough lumber 62, which has been simultaneously conveyed by the same means, will be carried from its visible position through openings in walls 26 and 68 through mill 12 to a hidden position behind wall 72 and extension 94 of member 84. This rough lumber will be discharged from the device to the rear, obscured from view, where it may be collected for further use by replacing it on the sloping wall 20 of station 28.

In Fig. 2 there is shown a constant speed motor 14 mounted to a bracket 100 which is affixed by conventional means to a portion of the mill 12. A ratchet gear 102 is mounted at the lower end of the drive shaft 104 and engages reduction gearing 16.

Affixed by screws or other suitable means to the walls 36, 38 (Fig. 9) of section 28, and rear wall 108 (Fig. 3) of mill 12, is a U-shaped bracket 110 (Fig. 9) to which is mounted the driving means for the lumber 60—62 which causes them to move in the direction of arrow 64 (Fig. 1).

These drive means includes a chain 112 threaded between the sprocket gears 114, 116 which are mounted on shafts 118, 120. These shafts freely rotate in openings 122 in bracket 110. This mounting is illustrated in Fig. 9 for one shaft and the other is mounted in like manner. The shaft 120 is connected through shaft extension 121 to a gear 125 from whence it receives its drive power.

Affixed to chain 112 is a paddle 130 by conventional means. This paddle has an upper arm 132 which extends substantially horizontal and will engage one end of the finished lumber plank 60 resting on extension 51 of bracket 50 in pocket 54.

The lower arm 134 of paddle 130 is substantially circular, and will engage the end of a round piece of rough lumber 62 resting on the inclined wall 20.

It is seen that as the chain is driven by means of motor 14 through gearing 16, shaft extension 121, gear 125 and shaft 120, the arms 132, 134 of chain paddle 130 will engage a piece of finished lumber and a piece of rough lumber and simultaneously carry them as hereinbefore described from station 28 to station 70 through openings in opposite side walls 26, 68 of mill 12. The rough lumber sliding along the rear edge 63 and 71 of wall 20 and the smooth lumber along portion 51 of partition wall 50 and flat portion 90 of member 84.

As paddle 130 approaches the shaft 116 the curved surface of the paddle arm 134 will engage the clip cam 136 mounted to flat portion 90 of member 84 (Fig. 6) and this clip cam will cause by its camming action, a pivoting of member 84, as hereinbefore discussed, about pin 86.

A second cam member 140 (Figs. 5 and 7) is also mounted on the inner surface of extension 94 of member 84 to insure that the rough logs will be positively ejected from the device towards the rear.

As the chain 112 continues in its path around shafts 118, 120 continuous operation results that will give the illusion to the observer of rough lumber being transported to the saw mill and coming out as finished planks.

As the rough lumber 62 moves into saw mill 12 under

the push of paddle 130 its lead end engages a contact arm 146 (Fig. 9). This arm is connected by means of a rod 148 to a fan shaped metal plate 150. Plate 150 (Fig. 2) is normally held in the position 150' away from rotating toothed gear 152 mounted to the upper end of shaft 104 by a spring 156 (Fig. 3).

As the arm 146 is moved by the lead end of log 62, it pivots metal fan 150 against the action of spring 156 so that the fan engages rotating toothed gear 152. The audible sound resulting from this contact will for all intents and purposes be a reproduction of the normal sound of a saw cutting lumber in a saw mill.

When the rear end of log 62 passes by the arm 146, and pressure is released from arm 146, spring 156 will disengage the fan 150 from gear 152 and return fan 150 to the position 150' for further action when arm 146 is engaged by the forward end of the next log 62 entering mill 12.

I have described what I believe to be the best embodiments of my invention. I do not wish, however, to be confined to the embodiments shown, but what I desire to cover by Letters Patent is set forth in the appended claims.

I claim:

25. 1. A toy converting mill simulating device comprising walls defining a simulated mill having an inlet and a discharge, conveyor means arranged to move from outside said mill through said inlet and out said discharge, a material receiving station including wall means for storing finished materials in a hidden location outside said mill adjacent said inlet and in the vicinity of said conveyor means, and for storing rough unfinished materials outside said mill adjacent said inlet in a visible location adjacent said conveyor means, and a finished material discharge station for delivering finished materials to a visible location adjacent the discharge of said mill, means on said conveyor to engage a finished piece of material and move it while hidden from view into said mill and through said discharge into a visible location on said discharge station and to engage a rough unfinished piece of material at a visible location adjacent the inlet of said mill and move it into said mill, and means cooperable with said conveyor to remove said unfinished piece of material to the interior of said mill.
30. 2. A toy converting mill simulating device according to claim 1 wherein said finished materials are simulated lumber planks and said unfinished materials are simulated rough logs.
35. 3. A toy article as in claim 1 including means for reproducing the audible sound of the mill sawing action while said simulated lumber is being conveyed through said mill from said simulated lumber receiving station to said simulated lumber discharge station.
40. 4. A toy converting mill simulating device according to claim 1 including a pivotally mounted platform at said discharge station arranged to receive finished material thereon and means to pivot said platform as the next succeeding piece of material is fed thereto whereby to dump the previously fed material down to a lower location at said discharge station.
45. 5. A toy converting mill simulating device according to claim 4 wherein said discharge station includes a hidden inclined deck to receive said rough unfinished materials and said pivotally mounted platform includes a skirt portion extending therebeneath and in the path of said deck to retain rough unfinished materials thereon, said skirt being movable with said platform as the next material is being fed thereto to release said rough unfinished material and permit it to roll down the inclined deck.
50. 6. A toy converting mill simulating device according to claim 5 wherein said means to pivot said platform includes means on said conveyor to contact said platform and tilt it during movement of said conveyor.
55. 7. A toy device for simulating the cutting action of a saw-mill and for simulating the cutting of rough lumber

into smooth lumber planks, said device including wall means defining a central simulated saw mill, having an inlet at one end and a discharge at the opposite end, platform means on each side of said saw mill including a loading station connecting said inlet and a discharge station connecting said outlet, said loading station including a vertical pocket for the storing of simulated finished lumber planks thereon in a position hidden from view and including an inclined ramp for the storage of simulated rough lumber logs thereon, conveyor means extending from said loading station through said mill to said discharge station, said conveyor means including means for engaging a finished piece of simulated lumber plank and a simulated rough log and moving each into said mill, means inside said mill for removing said simulated rough log from said conveyor means, said simulated finished plank being delivered to said discharge station at a visible location thereon.

8. The toy according to claim 7 including means inside

said mill for simulating the noise of a saw cutting lumber as said pieces are moved therethrough.

9. A toy converting mill simulating device comprising walls defining a simulated mill having an inlet and a discharge, conveyor means arranged to move from outside said mill through said inlet and out said discharge, means to store finished materials hidden from view and unfinished materials visible in a location adjacent said inlet, means on said conveyor to transport said finished and unfinished materials therewith, and means to remove the unfinished materials from said conveyor within said mill.
